CLAIM

The ornamental design for a bottle as shown and described.

DESCRIPTION

FIG. 1 is a front view of a bottle showing my new design, the rear, left side and right side views being identical thereto; FIG. 2 is a top view thereof;

FIG. 3 is a bottom view thereof; and,

FIG. 4 is a top perspective view thereof.

The broken lines showing of the lip of the bottle forms no part of the claimed design.
